UNITED STATES PATENT OFFICE.

WALTER T. FAIRALL, OF STOCKTON, CALIFORNIA.

COMBINED DOOR CHECK AND BURGLAR ALARM.

Application filed May 31, 1922. Serial No. 564,801.

To all whom it may concern:

Be it known that I, WALTER T. FAIRALL, a citizen of the United States, residing at Stockton, county of San Joaquin, State of California, have invented certain new and useful Improvements in Combined Door Checks and Burglar Alarms; and I do declare the following to be a full, clear, and exact description of the same, reference being had to the accompanying drawings, and to the characters of reference marked thereon, which form a part of this application.

This invention relates to an improved door check which may at the same time be used as an efficient burglar alarm, the principal object of my invention being to provide a device of this character which may be instantly applied to a door to merely serve as a check against undesired opening of the same; and which may in addition have a blank cartridge inserted therein which will be exploded when any forcing open of the door is attempted, so that the device will then serve not only to prevent opening of the door, but also as an effective burglar alarm, which by arousing the occupant of the room, will be a valuable aid in catching the prospective intruder before he can make good his escape.

Another object is to provide a device of this character which is absolutely harmless to handle, since I have designed and arranged the operating parts in such a manner that the trigger member which explodes the cartridge is never cocked until an actual attempt to open the door is made.

I have also made the device so that while strong and efficient, it is very light and small, and may easily be carried in a handbag or suitcase, either as a single unit, or as two separated parts. In the latter case, the cartridge may be left inserted in place, without the slightest danger that it will be accidentally exploded with jolting or disturbance of any kind, as when the owner rummages through his bag for other articles.

The device is therefore admirably suited not only for home use, being easily and quickly applied to a door by man, woman or child, but for use by persons travelling, and who are forced to stop over night at hotels and rooming houses about the honesty of the other persons in which nothing is known.

The user need only assemble the two parts, place the device in position against a door, and he may then retire with the assurance

that he and his property are safe from unwelcome intrusion. In the morning the device can be again removed and packed away without disturbing or removing the cartridge, if this has not been discharged during the night.

The device may also be made as a permanent attachment to a door.

These objects I accomplish by means of such structure and relative arrangement of parts as will fully appear by a perusal of the following specification and claims.

In the drawings similar characters of reference indicate corresponding parts in the several views.

Fig. 1 is a perspective view of the device as applied to a door.

Fig. 2 is a longitudinal section of the device detached with the parts in their normal positions.

Fig. 3 is a similar view showing the parts telescoped or moved together and the cartridge exploded.

Fig. 4 is a side view of the device when arranged to serve as a permanent attachment.

Referring now more particularly to the characters of reference on the drawings, the numeral 1 denotes a tube having fixed on one end a preferably forked prong member 2 adapted to engage a floor. Slidably mounted in said tube beyond the prong is a hammer or plunger 3 connected by means of a compression spring 4 to another tube 5 slidably mounted in that end of the tube 1 opposite to the pronged end, said tube 5 being provided on its outer end with a prong member 6 similar to the member 2 and adapted to engage a door.

Intermediate the prong 2 and hammer 3 is a chamber 7 for a blank cartridge 8, the latter being insertable through a slot 9 provided in the tube 1 adjacent the block 7.

The hammer is normally held from movement toward the cartridge, regardless of the compression of the spring 4, by means of a catch 10 engaging the hammer and formed as part of a flat spring 11 mounted onto the tube 1 and partly projecting into a slot 12 cut in said tube.

Beyond the hammer, and toward the tube 5, the spring 12 is provided with a cam surface 13 projecting into the tube 1 into the plane of the tube 5, said surface being engaged by the inner end of the tube 5 when the latter is moved to telescope into the tube 1 a predetermined distance, during which

movement the spring 4 is being compressed. The engagement of the surface 13 of the spring 11 by the tube 5 causes the free portion of said spring to be moved outwardly 5 of the tube 1, which withdraws the catch 10 from engagement with the hammer 3, and the latter, owing to the tendency of the compressed spring 4 to expand, will then move rapidly toward and will strike, the cartridge 10 ridge 8, exploding the latter and of course sounding an alarm.

When the tube 5 has moved a distance sufficient to so engage the spring-cam, further telescopic movement of said tube is 15 prevented by means of a collar 14 thereon which engages the outer end of the tube 1.

To apply the device to a door, the tubes 1 and 5 are telescoped just enough to place the spring 4 under compression somewhat, 20 and the prongs 2 and 6 engaged with the floor and door at a suitable angle, as shown in Fig. 1.

The door may then be opened slightly, until such opening movement has caused 25 the tubes to telescope one with the other to a point where the collar 14 will engage the tube 1 and prevent further telescopic movement, as previously described. At the same time, a cartridge, if present, will be exploded, but whether the cartridge is used or not, the door cannot be then opened further, 30 any more pressure exerted on the latter merely tending to bury the prongs deeper into the surfaces with which they are engaged.

It will be noted that until the two tubes are telescoped about to their limit, the hammer remains inactive, and cannot possibly accidentally move to explode the cartridge.

40 The tube 5, with the hammer and spring 4, form a complete unit independent of the tube 1, and may be withdrawn from the latter at will if this is desired.

In Fig. 4 I have shown a means whereby 45 the device may be permanently attached to a door, for use in office buildings and the like. In this type of device, the door prong 6 is replaced by a bracket 15 attached to the door a suitable distance from the floor, the tube 5 being pivoted therein. When not in use, the device stands vertically and is held 50 in such position by a ring 16 on the door, which may be slipped from over the upper end of the device at will.

55 From the foregoing description it will be readily seen that I have produced such a device as substantially fulfills the objects of the invention as set forth herein.

While this specification sets forth in detail 60 the present and preferred construction of the device, still in practice such deviations from such detail may be resorted to as do not form a departure from the spirit of the invention, as defined by the appended 65 claims.

Having thus described my invention, what I claim as new and useful and desire to secure by Letters Patent, is:—

1. A combined door check and burglar alarm comprising a pair of tubes slidably mounted together for telescopic movement, a cartridge chamber in one of said tubes, a hammer adapted to move toward said chamber, a normally slack compression spring 70 between the hammer and the inner one of the tubes, and means whereby when the tubes are telescoped together the spring will be compressed without any movement being imparted to the hammer until said tubes 75 have been so telescoped to a predetermined extent.

2. A combined door check and burglar alarm comprising a pair of tubes slidably mounted together for telescopic movement, a cartridge chamber in one of said tubes, a hammer adapted to move toward said chamber, a normally slack compression spring 80 between the hammer and the inner one of the tubes, a catch member normally and automatically engaging the hammer to hold 85 the same from movement toward the barrel, and a cam member projecting from the catch member into the path of movement of the inner one of the tubes and adapted to be engaged by the latter to cause the catch to be released from the hammer when said tube 90 has moved toward the hammer a predetermined distance.

3. A combined door check and burglar alarm comprising a pair of tubes slidably mounted together for telescopic movement, a cartridge chamber in one of said tubes, a hammer adapted to move toward said chamber, a normally slack compression spring 100 between the hammer and the inner one of the tubes, a catch member normally and automatically engaging the hammer to hold 105 the same from movement toward the barrel, a member formed with the catch member and adapted to be engaged by the inner one of the tubes after the latter has moved a certain distance, and means whereby such engagement will cause the catch to be disengaged from the hammer, whereby the latter is then free to move toward the barrel. 110

4. A combined door check and burglar alarm comprising an outer tube having a cartridge chamber adjacent one end, a catch member mounted on and projecting into said tube intermediate its ends, an independent tube slidable into the outer tube from the end thereof opposite the cartridge chamber, a hammer likewise slidable in said outer tube, spring means between the hammer and inner tube, said hammer abutting against the catch after the inner tube has been inserted a predetermined distance into the outer tube, means actuated by a further inward movement of said inner tube for releasing the catch from the hammer. 115 120 125 130

5. A combined door check and burglar alarm comprising an outer tube having a cartridge chamber adjacent one end, a catch member mounted on and projecting into said tube intermediate its ends, an independent tube slidable into the outer tube from the end thereof opposite the cartridge chamber, a hammer likewise slidable in the outer tube, spring means between said hammer and inner tube, said hammer abutting against the catch after the inner tube has been inserted into the outer tube for a predetermined distance, and a common means normally resisting withdrawal of the hammer when once seated against the catch and for causing the catch to be moved clear of the hammer by the continued inward movement of the inner tube a predetermined distance. 20
- 5 10 15
6. A combined door check and burglar alarm comprising an outer tube having a

cartridge chamber adjacent one end, a catch member mounted on and projecting into said tube intermediate its ends, an independent tube slidable into the outer tube from the end thereof opposite the cartridge chamber, a hammer likewise slidable in the outer tube, spring means between said hammer and inner tube, said hammer abutting against the catch after the inner tube has been inserted into the outer tube for a predetermined distance, and a common means normally resisting withdrawal of the hammer when once seated against the catch and for causing the catch to be moved clear of the hammer by the continued inward movement of the inner tube a predetermined distance. 25
